UNITED STATES PATENT OFFICE.

STEVEN HIBASCO, OF PALO ALTO, CALIFORNIA, ASSIGNOR OF ONE-HALF TO HENRY F. KAUGIESER, OF PALO ALTO, CALIFORNIA.

PISTON CONSTRUCTION.

Application filed May 18, 1925. Serial No. 31,163.

To all whom it may concern:

Be it known that I, STEVEN HIBASCO, a citizen of the United States, residing at Palo Alto, in the county of Santa Clara and State of California, have invented new and useful Improvements in Piston Constructors, of which the following is a specification.

This invention relates to improvements in pistons and has particular reference to a piston for use in reciprocating engines.

The principal object of this invention is to provide a piston which will eliminate the use of the ordinary piston rings.

Another object of this invention is to produce a piston which will be tight at all times.

A still further object is to provide a piston which will prevent scoring.

An additional object of this invention is to provide a piston which will permit of ample lubrication without pumping oil.

Other objects and advantages will be apparent during the course of the following description.

In the accompanying drawings forming a part of this specification, and in which like numerals are employed to designate like parts throughout the same,

Figure I is a side elevation of my improved piston,

Figure II is a cross section taken on the line 2—2 of Figure I,

Figure III is a bottom plan view of the piston head,

Figure IV is a cross section taken on the line 4—4 of Figure I,

Figure V is a cross section taken on the line 5—5 of Figure I,

Figure VI is a vertical cross section taken on the line 6—6 of Figure I,

Figure VII is a side elevation of one of the piston sections,

Figure VIII is a bottom plan view of Figure VII,

Figure IX is a top plan view of Figure VII, and

Figure X is a diagrammatic illustration showing the manner in which the sections overlap, with the side walls to extend in a flat plane, and

Figure XI is a perspective view of one of the filler blocks.

At the present time in engines, it is com-

mon to employ a piston having a plurality of expansion rings carried in the surface 55 of the piston. These rings cause scoring in the sides of the cylinder wall within which the piston moves and these rings also result in the pumping of oil into the explosion chamber of the cylinder, with the 60 result that the spark plugs become foul.

It is also very difficult to maintain the rings in such a condition that there will not be some leakage of the oil past the same.

I have, therefore, endeavored to provide 65 a piston which will prevent these difficulties and thereby construct a very useful and efficient device.

In the accompanying drawings wherein for the purpose of illustration is shown a 70 preferred embodiment of my invention, the numeral 5 designates a piston head which has flanges 6 and 7. Between these flanges the various sections of the piston side walls 75 are secured.

Referring to Figure II, it will be noted that there are four filler blocks designated by the numerals 8, 9, 11 and 12. These filler blocks have chamfered ends, as shown at 13 and 14 (see Figures VII, IX and XI). 80 To these filler blocks are riveted or otherwise attached as shown at 16, the main piston sections designated as a whole by the numeral 17. As these main piston sections are identical, in construction but one will 85 be described.

At 18 I have shown an upstanding portion, the edges of which are adapted to be contacted by the edges of the next adjacent sections and it will be noted by viewing 90 Figure VII that these edges are cut upon an angle as best shown at 19 and 21. They are also cut upon a bevel as shown at 22 (see Figures II and IV). This upstanding portion 18 is formed integral with a flange 95 23 from which flange the main wall of the piston depends. This main wall is also cut upon an angle which corresponds to the angle 19 above described and is a continuation of the angles 19 and 21 (see Figure VII). 100

The interior of each section is grooved as shown at 24 and 26, so as to provide expansion rings 27 and 28, respectively. The result of this construction is that when the four sections are assembled as shown in Figures I and VI, the angular cut edges of the 105

filler blocks and side wall sections will fit as shown in these two figures, presenting a piston of the standard shape.

After the sections have been thus assembled the expansion rings 27 and 28 are inserted within the piston, which tends to force the sections outwardly which are mechanically contracted and then inserted within the cylinder, the result being that the four sections will respond into intimate contact with the sides of the cylinder wall and when properly lubricated will form a perfect seal against any loss of energy leaking past the piston.

15 Further due to the long bearing surface side slap will be prevented due to the diagonal cuts 19 and 21 and the oil will be continuously applied to the cylinder walls, scraped therefrom and again applied, there-

20 by precluding any possibility of the oil passing above the piston head. Due to the large bearing surface between the filler blocks and the flange 6, it will be impossible for any gas to leak from a point above the piston to

25 a point within the piston.

This piston will not freeze under high speed, nor will it cause overheating of the oil in the engine, due to the large heating surface. This piston will also stop metal-
30 lizing of the oil which is commonly caused

by the rings scraping against the cylinder walls, with the result that the metal particles in the oil wear the bearings of the engine and decrease the efficiency thereof, the result being that this piston produces more 35 power and consequent economy.

It will thus be seen that I have provided a piston which will perform all of the objects above set forth.

It is to be understood that the form of my 40 invention herewith shown and described is to be taken as a preferred example of the same, and that various changes in the shape, size and arrangement of parts may be resorted to without departing from the spirit 45 of the invention or the scope of the subjoined claim.

Having thus described my invention, I claim:—

In a device of the character described, 50 a head having spaced flanges, a plurality of depending sections movably secured between said flanges, a filler block secured to each of said sections and interposed between said flanges, said sections having 55 their abutting edges cut upon an angle, and means for expanding said piston, for the purpose specified.

In testimony whereof I affix my signature.
STEVEN HIBASCO.
